UNITED STATES PATENT OFFICE.

ELISHA P. S. WRIGHT, OF SHORTHILLS, NEW JERSEY, AND ALBERT McCARTNEY, OF NEW YORK, N. Y.

FIREPROOF BUILDING CONSTRUCTION.

SPECIFICATION forming part of Letters Patent No. 727,250, dated May 5, 1903.

Application filed January 17, 1903. Serial No. 139,390. (No model.)

To all whom it may concern:

Be it known that we, ELISHA P. S. WRIGHT, residing at Shorthills, Essex county, New Jersey, and ALBERT McCARTNEY, residing at 5 New York, county and State of New York, citizens of the United States, have invented certain new and useful Improvements in Fire-proof Building Construction, of which the following is a specification, reference being had 10 to the drawings accompanying and forming a part of the same.

Our invention relates to that method of fire-proof construction in which concrete, cement, or similar plastic material is used in connection with iron or steel framework, and has 15 for its object not only to effect a considerable saving in material and the cost of manufacturing the same, but also to provide a system of construction which shall be more durable 20 and efficient in use and which can be carried out with less labor and expense than have heretofore been required to produce an equally efficient result.

To these ends it consists of the novel features and combinations hereinafter described, 25 and more particularly pointed out in the claims.

As well known, concrete, while possessing great resistance to crushing strains, has but 30 little tensile strength, so that a comparatively slight stress on an unsupported area of a block or slab will cause fracture of the same. It is therefore necessary to provide some means which will supply the desired resistance 35 to fracture—as, for example, by embedding iron or steel bars in the concrete. In one method which we have used with success T-bars were employed, the bars being preferably made by bending sheet metal. Such 40 bars, however, are costly both to manufacture and to use. We have therefore devised our present invention, of which an embodiment is illustrated in the drawings.

Figure 1 is a perspective; Fig. 2, a modification; Fig. 3, a detailed view of the saddle-clip. Figs. 4 and 5 are further modifications, the former a detail of the combined clips used 45 in the construction of Fig. 2.

11 represent flanged iron beams usually of 50 I form and arranged substantially parallel to each other, carrying between them a series of

supports 2 2. The latter are preferably provided with notches 3 3, in which rest clips of a saddle form. (Shown in detail in Fig. 3.) The clips or saddles 4 are easily and cheaply 55 made from suitable strips or bars by bending. The outstanding flanges 5 are bent at right angles to the sides and also twisted, so that in their broadest dimension they lie in a substantially vertical plane, as shown. They 60 are either hung on the supports loosely or may be fastened in any convenient way, as by riveting. At each end of the supports 2 it is desirable to use a clip of substantially the form just described, except that the flanges 65 thereof are not twisted. By this means the flanges of the clip rest firmly on the flange of the beams 1, and thus hold the supports against tilting. The metallic parts of the structure being thus assembled, a suitable centering—as, for example, 6—is arranged below 70 the former and a mass of concrete or other plastic material cast in position, as shown, embedding in its mass the supports and clips. The functions of the supports and clips will 75 now be clear. They constitute internal ribs which furnish to the casting the tensile strength and resistance to fracture which was before wanting, and at the same time the clips support the casting after the centering 80 6 has been removed.

The construction may be made in panel form, as shown in Fig. 2, by employing blocks 7, preferably of concrete or other plastic material, on which the supports 2 are placed instead of directly on the flanges of the I-beams. The centering 6 is then arranged substantially flush with the upper surfaces of the blocks and the cement cast thereon. It will 85 thus be seen that when the centering is removed the under side of the structure will 90 show a panel form particularly suitable for ceilings.

Where a specially strong construction is required, the desired increase of tensile 95 strength may be secured by doubling the clips in the manner shown in Figs. 2 and 4. In that case the second set of clips are arranged upon the first, preferably with the flanges of the latter extending in a horizontal plane, as 100 shown, for the purpose of affording a support for the casting without possibility of the

flanges shearing through under heavy loads, as might be the case if both sets of flanges were vertical. In the construction just described we prefer to rivet both clips to the support, as shown at 8. It will of course be understood that the use of doubled clips is not confined to the panel structure of Fig. 2.

By using the arrangement shown in Fig. 5 a strong construction may be obtained without employing a wide support, such as is illustrated in the other figures. As will be seen, a narrow support 2 is held a distance above the lower flange of the beam, while the clips extend below the support. This economical method we consider within the scope of our invention.

Practical use of the invention just described has demonstrated its cheapness and efficiency. At the same time we have found that it is capable of numerous modifications; but these are clearly within the scope of our invention, and we therefore do not consider ourselves limited to the precise embodiment shown.

What we claim is—

1. In fireproof building construction, the combination with a plurality of flanged beams, of a plurality of supports extending between said beams, flanged saddle-clips having outstanding flanges twisted to lie in a substantially vertical plane, and a mass of plastic material cast between said beams, embedding in the mass the supports and flanged clips, as set forth.

2. In fireproof building construction, the combination with a plurality of flanged beams, of a plurality of supports extending between said beams and resting on the

flanges thereof, flanged saddle-clips resting in notches on said supports having outstanding flanges twisted to lie in a substantially vertical plane, and a mass of plastic material cast between said beams, embedding in the mass the supports and flanged clips, as set forth.

3. In fireproof building construction, the combination with a plurality of flanged beams, of blocks resting on the flanges of said beams, supports extending between said beams and carried by said blocks, flanged saddle-clips on said supports having outstanding flanges twisted to lie in a substantially vertical plane, and a mass of plastic material cast between said beams upon a centering arranged substantially flush with the upper surfaces of the blocks, said mass embedding the supports and flanged clips therein, as set forth.

4. In fireproof building construction, the combination with a plurality of flanged beams, of a plurality of supports extending between said beams, flanged saddle-clips on said supports, having their flanges extending outward in a horizontal plane, flanged saddle-clips arranged upon the first-mentioned clips, having their flanges twisted and extending outward in a vertical plane, and a body of plastic material cast between said beams, embedding in its mass the supports and flanged clips, as set forth.
